UNITED STATES PATENT OFFICE

2,643,825

THERMOSTATIC DEVICE

Donald F. Drow, Los Angeles, Calif., assignor, by
mesne assignments, to Minneapolis-Honeywell
Regulator Company, a corporation of Delaware

Application February 10, 1950, Serial No. 143,555

10 Claims. (Cl. 236—48)

1

The invention relates to temperature responsive devices adapted to control the fuel flow to a burner of a heat appliance, and more particularly to adaptations of such devices to pilot operated safety valves designed to shut off the flow of fuel to a main gas burner upon extinguishing of the pilot burner of the appliance. In modern gas heat appliances, it is customary to use a thermostatically operated valve responsive to and controlled by a pilot burner which is mounted in proximity to a so-called main burner for ignition of the gas issuing from the main burner as the condition-responsive thermostat calls for heat. In such an installation, safety of operation depends upon the existence of a flame at the pilot burner when the operating thermostat turns on the gas to the main burner, so that the gas issuing from the main burner will be properly ignited and not permitted to escape and accumulate in the appliance or room containing the appliance, to thereby create a hazardous and explosive condition. Accordingly, a so-called pilot safety valve is incorporated in the installation, including a gas valve positioned in the fuel line to the main burner and which functions to close this valve and thus shut off fuel flow on failure or extinguishing of the pilot burner.

An object of the present invention is to provide a device of the character described which is constructed to withstand the high temperature to which it is continuously subjected in the fire box of the heat appliance, without deterioration of its ability to respond to temperature changes occurring on extinguishing of the pilot burner, so that the device will stand ever-ready to function throughout an indefinitely long period of time.

Another object of the present invention is to provide a device of the character above which will automatically function both to open and close a gas valve as the pilot burner is ignited and extinguished, respectively, thereby automatically providing for so-called safe lighting of the appliance without the use of any form of manual re-setting mechanism, in that gas flow to the main burner is positively prevented after extinguishing of the pilot burner and until after the pilot burner is again ignited and properly functioning.

A further object of the invention is to provide a device of the character described which will be relatively fast cycling, thereby insuring a minimum delay in shutting off of fuel flow following extinguishing of the pilot burner, and also minimum delay in re-establishing fuel flow after re-

2

ignition of the pilot burner, and in which the cycling operation may be conveniently and accurately adjusted to control the "on" and "off" times of the unit.

Still another object of the present invention is to provide a device of the character described having an improved snap action mechanism and operating assembly affording substantially greater valve displacement, thereby permitting the deletion of customary valve adjustments for insuring valve opening and at the same time obtaining greater capacity.

Yet a further object of the invention is to provide a device of the character above having an improved unitary mounting and assembly of the snap acting device, thermostat, and valve, and wherein this assembly and its operation is completely independent of the temperature and relative expansion or contraction of the valve body.

Yet another object of the present invention is to provide a device of the character described which is particularly designed for simplified low-cost construction, utilizing die cast body sections, a minimum machining of parts, and a general elimination of close tolerances in relatively moving parts, thereby obviating the danger of sticking or binding, with resultant failure of the device, when used with gases containing gummy substances or corrosive elements such as sulphur dioxide.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the same drawings and description may be adopted within the scope of the invention as set forth in the claims.

Referring to said drawings:

Figure 1 is a vertical cross-sectional view of a thermostatic device constructed in accordance with the present invention.

Figure 2 is a cross-sectional view of the device taken substantially on the plane of line 2—2 of Figure 1.

Figure 3 is a cross-sectional view on a somewhat enlarged scale of a portion of the device taken substantially on the plane of line 3—3 of Figure 1.

Figure 4 is a cross-sectional view of the device taken substantially on the plane of line 4—4 of Figure 3.

Figure 5 is a perspective exploded view showing

the parts and their respective relationships making up the clicker and valve assembly.

The thermostatic device of the present invention is illustrated in the accompanying drawing in an adaptation of such device to a pilot safety valve of the character above described. As will be clear from an understanding of the mechanism, various essential parts of the device may be used in other types of thermostatic devices, such as, for example, thermostats for controlling water temperature of an automatic gas fired water heater.

The device includes a casing 6 made up of three sections, 7, 8 and 9, providing a valve body and defining an interior valve chamber 11 having inlet and discharge passages 12 and 13 and a valve seat 14 controlling the gas flow through the chamber. In the design of the casing, the section 8 forms a central portion of the body and is of generally tubular form having open upper and lower ends which are engaged and sealed off by the top and bottom cover sections 7 and 9, sealing gaskets 16 and 17 being positioned between flat contacting surfaces of these sections and the assembly being clamped together in a rigid gas-tight enclosure by a screw 18 extending into the interior of the casing through an aperture 19 in the bottom cover 9 and threaded into a depending lug 21 on the top cover 7. Threaded tubular extensions or bosses 22 and 23 are formed on the top and bottom covers 7 and 9 for providing the inlet and discharge passages 12 and 13 and for connection to supply and discharge conduits 24 and 26. Also, the valve seat 14 is formed in the bottom cover 9 in surrounding relation to the discharge passage 13. The casing construction as described and as will be more apparent with reference to the parts of the device, has been specially designed for low-cost die casting of the sections and a simple, rapid, and yet highly effective attachment of the sections to define a gas-tight body with but the use of a single attaching screw.

Thermostatic operation of the device is obtained by means of a rod-and-tube type thermostat including telescopic tube 27 and rod 28 having different coefficients of thermal expansion, connected at their ends 29 and 31 to provide differential movement of their opposite ends 32 and 33 with temperature changes. As here shown, the end 32 of tube 27 is rigidly mounted and sealed in an opening 34 in a side wall of the body section 8 so that the extremity of the tube extends into the interior chamber of the casing. As shown in Figure 1, the tube is preferably mounted with its axis substantially perpendicular to the axis of the valve seat 14. A bearing member 36 is rigidly mounted in the open interior end 32 of the tube and is provided with a central opening 37 adapted to slidably receive the smooth cylindrical portion of a screw 38 having an end portion 39 threaded into the inner end 33 of the rod 28, the screw extending axially from the rod through the bearing opening 37 and provided with an enlarged head 41 spaced inwardly in the chamber from the bearing member 36. Carried on the screw 38 in abutment with its head 41 is a hub member 42 having a central aperture for axial mounting on the screw and which supports in an outer peripheral groove the inner periphery 43 of a concavo-convex, dish-shaped snap ring member 44. The member 44 is preferably constructed of thin spring material such as appropriate spring steel used for this purpose and capable of providing an over-center snap action

upon displacement of the outer periphery 46 of the ring to and past a flattened position of the ring. Such motivation of the ring to obtain an abrupt snap action is here effected by a plurality of radially extending levers 47 mounted between the opposed sides of the bearing and hub members 36 and 42 and engaged and displaced by concentric knife-edged fulcrums 48 and 49 thereon into pressure contact with the outer periphery of the ring 44. The levers may be formed, as best shown in Figure 5, from sheet metal stock with the several levers radiating outward from a ring-like center portion 51 having a central opening 52 mounted on the screw 38 so as to support the levers 47 symmetrically about the central axis of the assembly with the outer extremities of the levers contacting the outer periphery 46 of the ring member 44 on its normally concave side. As will be seen from Figures 1 and 5, the fulcrum 49 on the stationary bearing member 36 surrounds the opposed fulcrum 48 on the hub 42 so that upon movement of the hub 42 in the direction of the member 36 the levers will be swung against the outer periphery of the ring member 44 in a direction tending to flatten the ring and effect snap action. Contra-wise, on movement of the hub 42 away from the bearing member 36, the levers will be swung away from the outer periphery of the ring member, thereby permitting the latter to snap back to its original unstressed position as shown in Figure 1. In the construction of the ring member, its concavo-convex deformity is such as to cause the ring to snap over center as pressure is applied to its inner and outer peripheries as above described, but the extent of its original curvature is such that the ring will snap back to its normal position as such pressure is released.

As an important feature of the present construction, the ring member is formed with an integral arm extension 53 which projects from the outer periphery 46 of the ring member to provide an amplified, abrupt snap action movement of the outer free end 54 of the arm upon snap action of the ring member as above described. In the present construction, the arm 53 is bent from the general plane of the ring member so as to lie at substantially right angles thereto, with the outer end of the arm in opposed relation to the valve seat 44. The construction is also such that upon snapping of the ring by the levers 47 the free end of the arm will be abruptly swung in the direction of the valve seat and upon reverse snap action of the ring to its normal unstressed position the arm end will be swung away from the valve seat.

In the present device and as an important feature thereof, valve 56 is mounted directly on the outer end 54 of the arm and is carried thereby for movement into and out of engagement with the valve seat 14. The valve construction and its mounting on the arm is seen best from Figures 3 and 5. The valve body is here composed of a flat disc washer 57 rigidly secured to the head end 58 of a screw 59 threaded into a sleeve-type nut 61 mounted through an opening 62 in the arm end 54. A valve disc 63 of suitable compressible and sealing material such as rubber, neoprene or the like, may, as here shown, be directly attached, as by vulcanizing or other bonding, to the face of the washer 57 to provide a valve contact on the seat 14, or a direct metal-to-metal engagement may be provided. The sleeve nut 61 is retained on the arm by an enlarged head end 64 of the nut at one side of the arm 54 and a spring

retainer washer 66 at the opposite side of the arm, and supported on a shoulder 67 on the nut. Normally, the valve assembly is urged to a closed valve position by means of a pyramidal helical spring 68 having one end supported on the retainer washer 66 and its opposite enlarged base end carried in a spring retaining groove 69 formed in the cover section 6 concentrically of the inlet passage 12. It is important to note that the action of this spring is to constantly urge the valve to a passage-closing position, so that in the event of a failure of the device for any reason other than failure of spring 68, the fuel flow will be positively shut off.

Since an abundant movement is available at the outer end 54 of the arm for the purposes desired, a limited lost motion connection between the arm and valve is preferred in order to obtain a clean snap movement of the valve without graduation of movement. To accomplish this, the spring retainer washer 66 is supported on its shoulder 67 at a sufficient distance from the head end 64 of the nut so as to permit any graduation of movement of the arm occurring while the snap ring is displaced to and from its critical snap acting positions, to take place between the retainer washer and the head. The threading of the screw 59 into the sleeve nut 61 permits an easy and accurate initial setting of the valve, and preferably the shank of the screw is split and spread as illustrated to provide a tight fit to maintain the initial setting. Due to the large amplitude of movement at the outer end of the arm, the initial setting of the valve is not critical, and full valve opening and maximum fuel flow is at all times provided.

As another feature of the present construction, the rotative position of the snap ring 44 to maintain proper alignment of the valve and seat is insured and retained by utilizing the screw 18 as a positive guide for the arm. As will be seen from Figures 1, 2 and 5, the arm 53 is provided with a guide opening 71 intermediate its length through which is inserted the shank of the casing assembly screw 18, the axis of the screw being generally parallel to the axis of movement of the valve.

As hereinabove noted, the device herein disclosed is particularly designed for use with a pilot burner, and preferably such burner is mounted on the casing for insuring a precise relationship between the thermostat 27 and the pilot burner. As here shown, a pilot orifice fitting 72 is threaded into the side wall of the casing section 8 adjacent to the thermostat tube 27 and in generally parallel relation thereto. A conventional type pilot burner tube 73 is here fitted over the outer end of the fitting 72 and is formed with a primary air opening 74 adjacent the aperture discharge of the fitting to provide a usual Bunsen burner construction. The tube 73 extends axially from the fitting 72 in underlying parallel relation to the thermostat tube 27 and then curves upwardly at its outer end 76 to project somewhat above the outer end of the thermostat into proximity to the ports of a main burner (not shown). A series of burner openings 77 are provided along the length of the tube and around the upwardly curved end so as to play pilot flame onto the under side and end of the thermostat tube. The central section 6 of the body is provided with gas passages 78 and 79 (see Figures 3 and 4) leading from the orifice fitting 72 to a pilot intake passage 81 formed in a boss 82 on the side of the section. An intake conduit for pilot gas may be secured

as here shown in the inlet opening 81 by a conventional fitting 84. Desirably, a needle type valve 86 (see Figure 4) is provided in the passage 79 for regulating the gas flow to the pilot burner, and a removable plug 87 is provided in the wall of the section to permit access to the head 83 of the valve, the latter being threadably mounted in the body for adjusting action, as shown in Figure 4.

10 As will be seen from the foregoing, the thermostat tube end 32 and the associated inner end of the thermostat rod provide the sole means of support for the clicker or snap action assembly and the valve. Thus, a unitary thermostat, clicker and valve assembly is provided independent of the casing of the unit. Accordingly, the operation of this assembly is independent of the temperature or relative expansion or contraction of the casing. Preferably, the tube 27 is constructed of a material having a relatively large coefficient of thermal expansion and at the same time being resistant to high operating temperatures. Certain stainless steels available in the market are quite satisfactory for this purpose. Some are capable of withstanding constant temperatures in excess of 1,000° F. without scaling or developing brittling grain growth or inner granular carbide precipitation, and have a coefficient of thermal expansion of approximately 9.45×10^{-6} in. per degree F. The rod 28 may be made of invar steel or even cold rolled steel having a coefficient of expansion of approximately 6.7×10^{-6} in. per degree F. Preferably, the rod 28 is made of tubular construction throughout its length, or provided with an end bore over a majority of its length, as here shown, so as to reduce its mass and thereby render it more responsive to temperature changes. An over-all length of the tube and rod thermostat of about two and one-half inches is sufficient to provide adequate relative movement to operate the device. Of course, longer lengths of the rod and tube thermostat increase the amount of activating movement available. Up to about eight inches in length is more or less standard for water heater installations.

50 The assembly above described is thus capable of use in very high ambient temperatures which would preclude the use of other types of safety pilots. It is also highly sensitive to temperature changes and can be constructed with a minimum cycling time. A setting of the snap action mechanism for a full "on" and "off" operating cycle of about twenty to thirty seconds is preferred in order that minor variations in the pilot flame will not operate the device and yet the device will be rapidly responsive upon extinguishing of the pilot burner. The respective "on" and "off" times in such a cycle can be set by adjusting the screw 38 controlling the tension and pre-setting of the clicker assembly. In the present construction, access to the head end 41 of the screw is provided by a removable closure plug 89 threaded into the wall of section 8 in alignment with the screw 38. Also, an opening 91 is formed in the lug 21 in alignment with the screw and plug 89. On removal of the plug 89, a screwdriver or Allen wrench or the like (depending upon the type of socket formed in the screw head) may be inserted between the coils of spring 68, through aligned opening 91 and into engagement with the screw for effecting its adjustment. Thus, with an operating cycle of twenty-four seconds, the device may be set to afford a 6 seconds "on" time and 18 seconds "off" time, or any other combination of

"on" and "off" times making up the operating cycle. This adjustment may be easily made in the field by first shutting off the main gas valve leading to the appliance.

The normal cold position of the device is illustrated in Figure 1, wherein the valve 56 is in shut-off position. To place the device in operation, the pilot burner is ignited and heat is applied to the thermostat tube 27, causing its expansion. As the tube 27 expands, the hub 42 is displaced toward the bearing member 36, fulcruming the levers 41 against the outer periphery of the snap ring and causing it to snap to an over-center position, thereby swinging the integral arm 43 away from valve seat 14, and opening the valve. If thereafter the pilot burner becomes extinguished, the cooling of the thermostat tube 27 provides a reverse operation wherein the snap ring returns to its unstressed position, thereby abruptly displacing the valve to closed position, as illustrated in Figure 1. Since the device functions automatically to open and close the valve as above described, depending upon the presence or absence of pilot flame, no manual re-setting mechanism is required as in the case of other types of pilot safety valves. Also, due to this automatic opening and closing action, the unit inherently provides so-called safe lighting, in that no flow of gas to the main burner is permitted while the pilot burner is being ignited and until after the pilot burner is in proper operation.

I claim:

1. A thermostatic device comprising, a casing formed with an interior chamber having inlet and discharge openings and provided with a valve seat between said openings, a concavo-convex ring formed to snap through a center position in said chamber, a hub member supporting the inner periphery of said ring, means engaging the outer periphery of said ring on the concave side to afford snap action of said ring upon displacement relative to said hub member, thermostat elements having different coefficients of thermal expansion connected to said hub member and means for effecting relative displacement thereof and snap action of said ring means with temperature changes, an arm formed integrally with said ring and extending from the outer periphery thereof, the outer end of said arm being mounted in juxtaposition to said seat and being abruptly displaced to and from said seat upon snap action of said ring, a valve mounted for movement to and from said seat and actuated by the outer end of said arm, and guide means carried by said casing and coacting with said arm to maintain alignment of said arm and valve seat.

2. A thermostatic device comprising, a casing formed with an interior chamber having inlet and discharge openings and provided with a valve seat between said openings, a dish shaped member having an over-center snap action mounted in said chamber, opposed and concentric means engaging said member at radially spaced positions for displacing said member into and out of its over-center position upon relative movement of said means, thermostat means connected to said first means for displacing said member in accordance with temperature changes, an arm formed integrally with said dish shaped member and extending from the outer periphery thereof, the outer end of said arm being arranged in juxtaposition to said valve seat and being abruptly displaced upon snap action of said member to and from said seat, a valve mounted for movement to and from

said seat and actuated by the outer end of said arm, said arm being formed intermediate its length with an opening, and means carried by said casing and extending through said opening to prevent rotative displacement of said arm away from said valve seat.

3. A thermostatic device comprising, a casing formed with an interior chamber and a valve seat therein, a dish shaped member having an over-center snap action mounted in said chamber with the plane of said member substantially perpendicular to the plane of said valve seat, opposed and concentric means engaging said member at radially spaced positions for displacing said member into and out of its over-center position upon relative movement of said means, thermostat means connected to said first means for effecting relative displacement thereof and actuation of said member in accordance with temperature changes, an arm formed integrally with said dish shaped member and extending from the outer periphery thereof, said arm being bent from the plane of said dish shaped member adjacent said outer periphery thereof to lie in a plane substantially perpendicular thereto and with the outer end of said arm in juxtaposition to said seat and being abruptly displaced to and from said seat upon snap action of said member, and a valve mounted for movement to and from said seat and actuated by the outer end of said arm.

4. A thermostatic device comprising, inner and outer telescopically arranged members having different coefficients of thermal expansion connected at one end to provide differential movement of their opposite ends with temperature changes, a bearing member secured to the last mentioned end of said outer member and concentrically supporting said inner member for relative longitudinal movement, screw means carried by said inner member and provided with a hub in opposed position to said bearing member, a dish shaped ring formed to snap through a center position and mounted on said hub with the inner periphery of said ring supported thereby in concentricity with said bearing member, a plurality of radially extending levers mounted between said hub and bearing member and displaced thereby against the outer periphery of said ring to effect snap action thereof, an arm formed integrally with said ring and extending from the outer periphery thereof, the outer end of said arm being abruptly displaced upon snap action of said ring, and means adapted to be thermostatically operated connected to and actuated by the outer end of said arm.

5. A thermostatic device comprising, inner and outer telescopically arranged members of different coefficients of thermal expansion connected at one end to provide differentiation of movement of their opposite ends with temperature changes, a bearing member secured to the last mentioned end of said outer member, a screw slidably mounted for reciprocation in said bearing member concentrically of said outer member and threaded into the adjacent end of said inner member, a hub carried by the outer end of said screw in opposed position to said bearing member, a dish shaped ring formed to snap through a center position mounted on said hub with the inner periphery of said ring supported by said hub in concentricity with said bearing member, a plurality of radially extending levers mounted between said hub and bearing member and displaced thereby against the outer periphery of said ring to effect snap action of said ring upon

relative movement between said hub and bearing member, an arm formed integrally with said ring and extending from the outer periphery thereof, the outer end of said arm being abruptly displaced upon snap action of said ring, and means adapted to be thermostatically operated connected to and actuated by the outer end of said arm.

6. A thermostatic device comprising, a casing formed of a plurality of sections and providing an interior chamber and a valve seat therein, a dish shaped member having an over-center snap action mounted in said chamber, opposed and concentric means engaging said member for over-center actuation thereof, thermostat means connected to said first means for effecting displacement thereof and actuation of said member in accordance with temperature changes, an arm formed integrally with said dish shaped member and extending from the outer periphery thereof, the outer end of said arm being abruptly displaced upon snap action of said member, means adapted to be thermostatically operated actuated by the outer end of said arm, said arm being formed with an opening intermediate its length, and a member engaging said sections for clamping said casing together and being formed with a portion extending through said chamber and passing through said opening in said arm in alignment with the direction of displacement of said arm to provide a guide for maintaining alignment of said outer end of said arm with said last named means.

7. A thermostatic device comprising, a casing formed of a plurality of sections and providing an interior chamber and a valve seat therein, a dish shaped member having an over-center snap action mounted in said chamber with the plane of said member substantially perpendicular to the plane of said valve seat, opposed and concentric means engaging said member for over-center actuation thereof, thermostat means connected to said first means for effecting displacement thereof and actuation of said member in accordance with temperature changes, an arm formed integrally with said dish shaped member and extending from the outer periphery thereof, said arm being bent from the plane of said dish shaped member to lie in a plane substantially perpendicular thereto and with the outer end of said arm in juxtaposition to said seat and being abruptly displaced to and from said seat upon snap action of said member, a valve carried by the outer end of said arm for movement to and from said seat, said arm being formed with an opening intermediate its length, and a screw member engaging said casing sections for clamping said casing together, said screw member extending into said chamber and passing through said opening in said arm to provide a guide for maintaining alignment of said valve with said seat.

8. A thermostatic device comprising, a casing formed of a plurality of sections and providing an interior chamber and a valve seat therein, a thermostat consisting of inner and outer telescopically arranged members of different coefficients of thermal expansion connected at one end to provide differential movement of their opposite ends with temperature changes, the last named end of said outer member being secured to and supported by said casing and extending into said chamber along an axis substantially perpendicular to the axis of said valve seat, a bearing member secured to said last

named member end, a screw slidably mounted for reciprocation in said bearing member with the head end of said screw in said chamber and the opposite end threaded to the adjacent end of said inner member, a hub carried by said screw at the head end thereof in opposed position to said bearing member, a dish shaped ring formed to snap through a center position mounted at its inner periphery on said hub, levers mounted between said hub and bearing member and displaced thereby against said ring to effect snap action thereof, an arm formed integrally with said ring and extending therefrom substantially perpendicular to the plane of said ring with the outer end of said arm in juxtaposition to said seat, a valve carried by said arm end for movement to and from said seat, a helical spring normally urging said valve to said seat and mounted with its axis extending across the axis of said screw in spaced relation to the head end thereof, a removable part for said casing substantially aligned with said screw axis affording access through the coils of said spring to the head end of said screw for adjustment of the relative positions of said hub and bearing member.

9. A thermostatic device comprising, inner and outer telescopically arranged members having different co-efficients of thermal expansion providing a differential movement of adjacent ends of said members with temperature changes, screw means carried by said inner member end and provided with a hub, an overcenter snap-acting ring member mounted on said hub for movement therewith, means mounted in fixed relation to said outer member end and engaging said ring member to provide snap action thereof upon relative movement of said hub, said screw means providing adjustable positioning of said hub relative to said last named means, and means adapted to be thermostatically operated connected to and actuated by said ring member.

10. A thermostatic device comprising, a casing providing an interior chamber with a valve seat therein, inner and outer telescopically arranged members having different co-efficients of thermal expansion providing a differential movement of adjacent ends of said members with temperature changes, said outer member end being secured to said casing, screw means carried by said inner member end and projecting axially therefrom into said chamber and provided with a hub movable in said chamber in accordance with temperature changes, an overcenter snap ring member mounted on said hub for movement therewith, means in said chamber providing a fixed support engaging said ring member concentrically to said hub to provide overcenter snap action of said ring member upon said movement of said hub, a valve connected to said ring member and being abruptly displaced thereby to and from said seat, said screw means being formed with a tool engaging portion exposed in said chamber, and a removable part for said casing affording access therethrough for engagement with said tool portion of said screw means for adjusting the position of said hub relative to said fixed support means.
